DESIGN FOR A TABLE TOP TRAY

Edward A. Storch, Detroit, Mich.

Application January 13, 1945, Serial No. 117,419

Term of patent 3½ years

(Cl. D44—10)

To all whom it may concern:

Be it known that I, Edward A. Storch, a citizen of the United States, residing in Detroit, in the county of Wayne and State of Michigan, have invented a new, original, and ornamental Design for Table Top Trays, of which the following is a specification, reference being had to the accompanying drawing, forming a part thereof, wherein:

ing a central raised portion and having depressions formed on the four sides thereof, showing my new design;

I claim:

The ornamental design for a table top tray, substantially as shown and described.

EDWARD A. STORCH.
